DESIGN FOR A GLOVE

Irwin Steinberger, New York, N. Y.

Application April 13, 1938, Serial No. 76,474

Term of patent 3½ years

To all whom it may concern:

Be it known that I, Irwin Steinberger, a citizen of the United States and a resident of the city of New York (Borough of Manhattan), in the county of New York and State of New York, have invented the new, original, and ornamental Design for a Glove, of which the following is a specification, reference being had to the accompanying drawing forming part thereof, in which

Fig. 1 is a front elevation of a glove showing my new design, and

Fig. 2 is a back view of the glove shown in Fig. 1.

The essential feature of my new design is the combination on the glove as shown of the specific front panel extending from the wrist and including the thumb in association with the specific panel on the back of the glove which includes the little finger.

I claim:

The ornamental design for a glove, substantially as shown and described.

IRWIN STEINBERGER.
